UNITED STATES PATENT OFFICE.

WILLIAM WALLACE HANSCOM, OF SAN FRANCISCO, CALIFORNIA.

CABLE-RAILWAY PROPULSION.

SPECIFICATION forming part of Letters Patent No. 292,165, dated January 22, 1884.

Application filed October 3, 1883. (No model.)

To all whom it may concern:

Be it known that I, WILLIAM WALLACE HANSCOM, a citizen of the United States, residing at San Francisco, in the county of San Francisco and State of California, have invented a new and useful Improvement in Cable-Railway Propulsion, of which the following is a specification.

My invention has for its object the raising 10 of the upper cable where in cable-railways two lines cross each other, so that as the grip attached to the under cable comes along and raises up the under cable it will not touch the upper cable, and thus will avoid the rubbing of one cable against the other. This is accomplished by the under cable, as it is raised up by the passing grip, acting upon suitable mechanism, which at the same time raises the upper cable and prevents their contact.

20 In the drawings accompanying this specification, Figure 1 is a vertical section through the tubes at or near the point of crossing of two lines of cable-railway; and Fig. 2 is a horizontal section of the tubes at the same 25 point, and each showing the construction and arrangement of the mechanism for the purpose.

H is an arm or bar hinged at I, so as to swing vertically, and carrying the sheaves E, 30 F, and G, the sheave E being above the cable C, (which is the under of the crossing cables,) and F being below it, and both in line with it. The sheave G is under and in line, or nearly so, with the upper cable, D, so that as it is raised up it will lift the cable D and keep it 35 from contact with the cable C. The sheave E is arranged on the swiveling spindle J, so that as the grip comes along it will push the sheave one side, and the spring K will swing it back 40 to its place again after the grip has passed. The end of the bar H is turned down at L, and rests upon a support, M, when the rope is in its normal position upon the carrier-sheaves in the tube.

45 O is the grip, shown at the height at which it runs in the tube when attached to the car to be propelled, and the dotted line C' shows the height at which the rope is carried in the grip, C being its normal position on the carrier- 50 sheaves, the height at which the grip runs above the carrier-sheaves being regulated by its construction and the conditions under

which the rope has to be operated, and consequently, the height that the rope is raised above the carrier-sheaves being dependent on 55 these conditions, it becomes necessary to so construct the grip that the rope may be raised the least possible distance above the sheaves which carry it.

For clearness in the drawings the distance 6c shown between C and C' is more than is required in actual practice.

The dotted lines C', D', E', F', and G' indicate, respectively, when raised by the passing grip, the positions of the under cable, C, the 65 upper cable, D, the upper sheave, E, the under sheave, F, and the sheave G under the upper cable, D.

The operation is as follows: As the grip when attached to the cable C carries it above 70 the carrying-sheaves which support the cable along the line, the sheave E resting upon it will be raised when the grip is yet some feet distant from the crossing of the cables, and this will raise, through its connection with the bar 75 H, the sheave G, which comes in contact with the cable D, and raises this also, the height of the sheaves E and G being so adjusted in reference to each other that the two cables C and D will be kept a proper distance apart. 80

When the grip-jaws are opened and the rope released, the rope will drop down on the roll F and carry with it the bar H until the end L rests upon the support M, and the rope D will drop down also and allow the grip O to pass 85 over it. By this means the grip of a car attached to the under cable may approach very closely to the crossing or upper cable or rope before releasing the rope to which it is attached, and the distance to which the car will 90 have to be propelled by its momentum will be lessened very materially in order that the grip may be carried beyond the crossing or upper cable, so that the under rope or cable may again be picked up. This is especially important 95 where there are steep grades approaching the crossings, as the momentum of the train at the usual speed allowed in cities is not sufficient to carry or propel the train more than a short distance. 100

Having fully described my invention, what I claim, and desire to secure by Letters Patent, is—

1. In a cable-railway having an underground

slotted-tube mechanism, substantially as described, whereby the upper of two or more crossing-cables may be raised and lowered and operated by the under cable or cables, so that 5 a proper distance may be maintained between the upper and under of the crossing cables, for the purposes set forth.

2. The swinging bar H, in combination with the sheaves E and G and two or more crossing cables of a cable-railway, substantially as 10 described and set forth.

3. The swinging bar H and swinging sheave E, in combination with the under sheave, F, and the cable C, substantially as described.

15 4. The swinging bar H, in combination with the sheaves E F G and the crossing cables C and D, substantially as and for the purpose described.

5. The combination, in a cable-railway where

cables cross each other, of a grip for attaching 20 the under cable to the moving car or train, two or more cables crossing each other, and suitable mechanism adapted and arranged to be operated by the under cable for raising the upper cable or cables, for the purposes set forth. 25

6. The swinging sheave E, in combination with a grip and crossing cables of a cable-railway, substantially as described.

7. In a cable-railway where two or more cables cross, a stop, substantially as described, 30 for limiting the movement of the mechanism which raises and lowers the upper of the crossing cables, for the purposes set forth.
